AIR CONDITIONER CABINET

Donald A. Schneider, Birmingham, Mich., assignor to
General Motors Corporation, Detroit, Mich., a corpora-
tion of Delaware

Filed Sept. 16, 1965, Ser. No. 87,029

Term of patent 3½ years

(Cl. D62—4)

Fig. 2

Fig. 3

FIGURE 1 is a perspective view of an air conditioner cabinet showing my new design;

FIGURE 2 is a front view of the air conditioner; and,

FIGURE 3 is a right side view of the air conditioner. The left side, not shown, is similar to the right side shown in FIGURE 3. The rear is not ornamental and may be plain.

The dominant feature of my design resides in the portions shown in the full lines.

I claim:

The ornamental design for an air conditioner cabinet, as shown and described.
